UNITED STATES PATENT OFFICE.

EARL D. RADER, OF NEW YORK, N. Y., ASSIGNOR TO DEXTER FOLDER COMPANY, OF NEW YORK, N. Y., A CORPORATION OF NEW YORK.

FOLDING MACHINE.

Application filed June 15, 1920. Serial No. 388,187.

To all whom it may concern:

Be it known that I, EARL D. RADER, a citizen of the United States, residing at New York, county and State of New York, have invented certain new and useful Improvements in Folding Machines, of which the following is a specification.

This invention relates to folding machines in which sheets are fed from a suitable source, such for example as a pile holding support or table, to suitable folding mechanism where they are folded. The primary object of my invention is to provide an improved construction and arrangement of parts in a machine of this character whereby a more positive control of the sheets is secured while at the same time making it possible to eliminate certain parts which are usually considered to be indispensable in machines of this character as heretofore constructed. Another object of the present invention is to provide improved sheet-feeding and folding mechanism including a stationary sheet-support, sheet-gripping means travelling in a closed path and adapted to close on the forwardly presented edge of a sheet on said sheet-support and to drag it into position to be folded by suitable sheet-folding means arranged along the path of said sheet-gripping means. For this purpose, the invention contemplates suitable means for operating the sheet-gripping means and engaging the forward edge of said sheet for registering it with respect to said sheet-folding means. One of the objects of the present invention is to provide an improved gripper construction, a suitable carriage therefor, and simple and efficient means for operating said grippers during the sheet conveying movements of the carriage. Another object is to provide an improved arrangement of conveyers, folding blades and grippers whereby said folding blades may be made to cooperate directly with the grippers for folding a sheet as the folded edge of said sheet is delivered to the grippers, or whereby a sheet may be delivered from one set of grippers to another set of grippers without a folding operation.

Other and further objects of invention will appear in the specification and be pointed out in the appended claims, reference being had to the accompanying drawings which exemplify my invention in a preferred embodiment.

In the drawings:

Figure 1 is a top plan view of a preferred embodiment of my invention;

Figure 2 is a side elevation and section of the same taken on the line 2—2, Figure 1;

Figure 3 is a front elevation of the same;

Figure 4 is a fragmentary top plan view and section corresponding to the line 4—4, Figure 16;

Figure 5 is a longitudinal section on the line 5—5, Figure 1;

Figure 6 is a top plan view on an enlarged scale of parts shown in Figure 1;

Figure 7 is a view in elevation from the right side of the lower portion of Figure 1, showing the delivery tapes;

Figure 8 is a section on the line 8—8, Figure 2;

Figure 9 is a top plan view of the carriage and gripper mechanism of the first and second conveyers in transfer relation corresponding to Figure 21, parts being shown in section;

Figure 10 is a fragmentary side elevation or inner face view of the frame, cams and carriage guides shown in Figure 9; (the folding cam being removed)

Figure 11 is a view similar to Figure 10, with the fold control cam in position;

Figure 12 is a top plan view of Figure 11;

Figure 13 is a section on the line 13—13, Figure 12;

Figure 14 is a fragmentary side elevation from below of the frame according to Figure 9;

Figure 15 is a section on the line 15—15, Figure 14;

Figure 16 is an inside elevation of the frame adjacent the delivery conveyers, parts being shown in section;

Figure 17 is a section on the line 17—17, Figure 3, parts being shown in plan;

Figure 18 is a side elevation corresponding to the line 18—18, Figure 17, parts being shown in section;

Figure 19 is a side elevation of one of the 5 grippers, parts being broken away and parts shown in section;

Figure 20 is a view similar to Figure 19, showing the relation of these parts to the front gage or sheet stripping fingers;

10 Figure 21 is a side elevation of cooperating grippers of two successive conveyors at the instant the folded sheet is transferred from one to the other, parts being shown in section;

15 Figure 22 is a perspective view of the several parts at the first fold mechanism, parts being shown in section;

20 Figure 23 is a combined side elevation and section of a modified gripper construction;

Figure 24 is a longitudinal section of another embodiment of my invention, parts being shown in side elevation;

25 Figure 25 is a side elevation on an enlarged scale of a portion of the gripper mechanism, parts being shown in section; and

Figure 26 is a rear elevation of Figure 25.

According to the embodiment of my invention shown in Figures 1 to 23 inclusive, 30 a table or support 1 is preferably provided with a top plate 2 which projects forwardly over the conveyor to be presently referred to, said top plate being provided with notches 3 (see Figure 6). According to the present

35 embodiment of my invention, the foregoing parts are arranged at the top and rear of side frames 4 and 5 shown best in Figures 1, 3 and 6. As shown in Figures 1 and 4, the 40 side frame 4 is provided near its top with a continuous guiding groove or track 6, while according to Figures 1 and 6, the side frame 5 is provided with a continuous guiding groove or track 7. Within the grooves 6 and

45 7 travel the supporting rollers of a gripper carriage which is preferably constructed similarly to that shown in Figure 9 of the drawings. Thus, a description of one of these carriages will suffice for all. Referring 50 to Figures 9 and 21, said carriage comprises oppositely disposed side frames 8 connected by a transverse bar 9, each of said side frames 8 being provided with carrying rollers 10 which run in the grooves 6 and 7

55 or other grooves of similar nature thereto. Secured to the cross bar 9 are a plurality of bearing brackets 11 (see Figure 9) within

60 which is journalled a gripper shaft 12. Said gripper shaft is provided on one end with a bevel pinion 13 which meshes with a bevel segment 14 carried by a lever arm 15 which is pivotally mounted on a stud 16 and adapted to be oscillated by a cam arm 17 which carries a cam roller 18. A spring rod 19

65 which carries a spring 20 interposed be-

tween the head of said rod and a fixed lug 21, is pivotally connected at 22 with the cam arm 17. Said spring tends to hold the grippers in closed position. Suitable means for propelling the carriage along its path of movement are provided as follows. Journaled in the side frames 4 and 5 are parallel shafts 23 and 24, the rear shaft 23 being provided with laterally spaced sprockets 25 and the front shaft 24 being provided with laterally spaced sprockets 26. Running on the sprockets 25 and 26 are chains 27 which are connected in driving relation to said carriage by means of a connecting link 28 (see

Figure 1) on each end of the carriage. As shown best in Figures 19 and 20, the cross bar 9 carries a transverse series of blocks

29 which are provided on their outer extremities with gripping elements 30. Mounted on the oscillatory shaft 12 are a plurality 35 of movable gripping elements 31 which have their outer ends deflected so as to conform to the gripping elements 30. In the embodiment shown in Figures 19 and 20, a leaf

32 spring which is secured to the movable jaw 31 of the gripper, carries a gripping element 33 which is adapted to yieldably clamp the sheets to the fixed gripper elements 30. Extending longitudinally of the

40 conveyor and partly around the forward shaft 24, is a web or plate 34 which in the present instance is adapted to support the trailing portion of the sheet which is being fed by the conveyor. A similar web or plate

35 (see Figure 5) is provided below the lower run of the uppermost conveyor for a similar purpose, the latter web or plate, however, being provided with a slot 36 for accommodating the folding blade at the first fold. Extending upwardly and part way around the sprocket 25, according to Figure 5, is a cam track 43^a which is suitably disposed to engage the cam roller 18 on that end of each gripper mechanism. The gripper mechanism is thus opened below and permitted to close above upon the forward edge of a sheet which is being presented on the stationary

45 table or support 1. Suitable and efficient means for locating the sheet at the first fold are provided by a front gage, which in the present embodiment, is provided in the form of a plurality of stripper fingers 37. Said stripper fingers 37 are spaced along a transverse bar 38 which is carried by laterally spaced supports 39 which have threaded connections with the longitudinal rods 40. As shown in Figures 1 and 5, the longitudinal rods 40 are cooperatively connected by a

50 transverse shaft 41 to which they are geared and one of the rods 40 is provided with a hand crank 42 for effecting the adjustment of the stripper fingers 37 together with the gripper releasing cam 43, which is mounted on the left hand support 39. It will be

55 understood that whenever the cam roller 18

(see Figure 9) runs over the cam 43, the shaft 12 will be oscillated in its bearings in a direction to open the gripper jaws 31. At the beginning of this movement, the yieldable gripping elements 33 effect a yieldable pressure on the sheet as it is brought into engagement with the stripping fingers 37. Said sheet is therefore registered by having the front edge straightened as it is stripped from the grippers. Keyed to rock shaft 44 between the upper and lower runs of the upper conveyer 27 are the laterally-spaced knife blade supporting arms 45 which carry a folding blade 46. As shown in Figure 22, the folding blade 46 is provided with laterally spaced notches or recesses 47 corresponding to the grippers 30, 33 on the sheet conveyers. It will appear from Figures 5 and 22 that as the folding blade 46 is moved downwardly, the sheet S is creased and its folded edge passed through the slot 36 separating plates 35 and delivered between the closing jaws of the grippers 30, 33 which are brought into suitable transfer position by the second conveyer 47'. The second conveyer 47' comprises laterally spaced chains mounted on sprockets 48 and 49 which are keyed to shafts 50 and 51. As shown in Figure 5, a cam track 43^b extends upwardly around the rear edge of sprocket 48 and forwardly to a point adjacent to the folding blade 46 in its lowered position. It will be understood therefore, that as the cam roller 18 on each gripper mechanism strikes the cam track 43^b the grippers are thrown into open position, as shown at the right end of the second conveyer according to Figure 5. As said cam roller leaves the forward end of said track bar, the grippers are permitted to close as shown at the left end of said second conveyer according to Figure 5. From the foregoing description, it will be understood that the endless chains 47' of the second conveyer, move the sheet-gripping means continuously over a closed path including an upper run extending toward the folding blade in its lowered position and a lower run extending in the opposite direction. Extending between the upper and lower runs of conveyer 47' is a rock shaft 52 to which are keyed lever arms 53 which carry a second folding blade 54 having a construction substantially similar to that already described. As the grippers of the second conveyer are moved rearwardly along the lower run of its travel, the folded edge of the sheet is brought against the stripping fingers 55 at approximately the same instant that said grippers are opened by a cam 56 which is preferably rigidly connected to the stripper fingers 55 and adjusted therewith by means of threaded rods 57 which are geared together by a transverse shaft 58 and operated by a crank 59. As the folded edge of the sheet is brought against the stripper fingers 55, it

is registered in the manner pointed out above in connection with the first fold. The second folding blade 54, as it moves downwardly, is adapted to impart a second parallel fold to the sheet as it forces the folded edge through a slot or opening 60 in the plate or table 61. This operation is timed in such a way as to place the folded edge between the closing jaws of grippers 29, 31 which are moved in their orbit by a third conveyer 70 comprising laterally spaced chains 62 which are driven by sprockets 63 and 64 keyed to shafts 65 and 66. Should it be desired to omit the second fold, the once folded sheet may be transferred from the second to the third conveyers by rendering the second folding blade 54 inoperative and by adjusting the relative positions of the second and third conveyers so as to bring the grippers on the second conveyer which hold the folded edge 80 of the sheet into suitable position to release said folded edge at the same instant that the grippers of the third conveyer are brought into position to grip the folded edge. The relations of the several parts for this operation are shown in Figures 9 and 21. For this purpose, a cam 67 is provided on the inner face of side frame 5 to open the upper grippers whereas on the inner face of the opposite side frame 4, a cam 68 is provided 90 which has previously opened the lower grippers and permits them to close again on the folded edge of the sheet as the upper grippers are released therefrom. It will be understood by an inspection of Figure 21 that the yieldable clamping pressure of the upper grippers is gradually released while the similar pressure of the lower grippers is gradually applied.

As shown in Figure 10, the cam 68 terminates at a point which will cause the lower grippers to close before they reach the rear turning point of the third conveyer. Suitable and efficient means for modifying this cam to open the grippers at a somewhat later time to correspond to the folding operation, may be provided by the cam plate 69 which is provided with a lug 70 to adapt it to be secured in position by a bolt 71 which passes through the side frame 4, as shown in Figures 11, 12 and 13.

According to Figure 5, the third conveyer is moving a once folded sheet through its lower run above a sheet supporting plate or table 72. After said sheet is conveyed to the left, according to Figure 5, it is moved upwardly and around a series of laterally spaced guide strips 73 on to an upper level below the left end of a transverse conveyer according to Figure 3. Said transverse conveyer comprises conveyer chains 74 mounted on sprockets 75 and 76 which are keyed to shafts 77 and 78. Arranged between the upper and lower runs of the third conveyer is a third folding blade 79 which is

shown in elevation in Figure 5 and in dotted lines in Figure 3. Said folding blade is carried by suitable lever arms 80 which are keyed to a rock shaft 81. The arrangement 5 or timing of the third folding blade 79 is such that it is adapted to impart a fold transverse to the first and second folds and to present said third fold to the closing grippers of conveyer 74. As indicated in 10 Figure 3, the sheet thus folded moves upwardly and over the upper run of conveyer 74 and thence downwardly at the right end of said conveyer and along the lower run thereof until it is registered by the striping fingers or front gage 82 which may be 15 adjusted with a gripper operating cam 83 by means of a crank 84. The twice or thrice folded sheet is thus brought under a fourth folding blade 85 (see Figure 3) carried by 20 the spaced arms 86 which are keyed to a rock shaft 87. As the sheet is thus folded for the third or fourth time, it is moved downwardly through a gap 86' and into position between conveyer belts 87' and 88 25 which move it downwardly between pressure rolls 89 and 90 to be delivered over the upper run of belts 87' on to a fly 91 which, as shown in Figure 18, is mounted on a rock shaft 92 which also carries a gear 93 meshing 30 with a gear segment 94. Said gear segment 94 is carried by a sleeve 95. As shown in Figure 3, the sleeve 95 is provided with a crank arm 96 which is connected by a red 35 97 to a cam yoke 98. A cam roller 99 on the inner face of said cam yoke runs on a cam 100 on the cam shaft 102. As shown in Figure 18, a pawl 103 which is pivoted at 40 104 on the gear segment 94 is adapted to operate a ratchet 105 which is keyed to a shaft 106 for driving a conveyer belt 107.

Referring to Figure 2, a motor 108 is bolted to the main frame of the machine, said motor being provided with an armature shaft 109 to which is keyed a pulley 110. A 45 belt 111 connects the pulley 110 to a driven pulley 112 which is keyed to shaft 65. Said shaft 65 drives the third conveyer in the manner hereinbefore pointed out. Keyed to the shaft 65 is a spur gear 113 which 50 meshes with a gear 114 which, as shown in Figure 8, is provided with an elongated hub 115 journaled upon a stub shaft 116. Rigidly mounted upon the outer end of hub 55 portion 115 is a cam 117, said cam being provided with an arcuate slot 118 (see Figure 2). Slidable within the slot 118 is a stud 119 (see Figure 8) which is threaded into a cam plate 120. By loosening the stud 119, the cam plates 117 and 120 may be 60 adjusted angularly to each other so that the shaft 65 may be adjusted angularly for the purpose of correlating the operations of the grippers on the second and third conveyers when it is desired to transfer a folded sheet 65 from one to the other without including

the second fold in the series of operations performed upon the sheet. As shown in Figure 8, the cam plate 120 is formed integrally with a sleeve 121 which is journaled on the elongated hub 115 of gear 114. Also integral with the sleeve 121 is a spur gear 122 which meshes with a gear 123 keyed to a shaft 124 upon which is freely journaled an idler gear 125 which meshes with the gear 114. As shown in Figures 1 and 6, 70 idler 125 meshes with a gear 126 which is keyed to the transverse shaft 51. As shown in Figures 1 and 2, the shaft 51 extends across the machine and is provided adjacent the side frame 4 with a gear 127. Gear 127 meshes with an idler 128 which in turn meshes with a second idler 129 which transmits power to a third idler 130 meshing with a gear 131 which is keyed to the shaft 24 75 for driving the first conveyer. The second conveyer is driven directly from the transverse shaft 51 which transmits power to the first conveyer. Operating upon the cam plate 117 is a cam roller 132 which is journaled in one arm of a cam lever 133 pivotally mounted on a stud 134 and having its other arm pivotally connected to a rod 135, the upper end of said rod 135 being pivotally connected to an arm 136 which is keyed to rock shaft 44 and serves to impart the oscillatory movements to the first folding blade 85. A cam lever 137 which is pivotally mounted on a stud 138, carries a cam roller 138' which operates upon the cam 120. A connecting rod 139 has one end pivotally connected to the cam arm 137 and its other end is pivotally connected to an arm 140 which is keyed to the shaft 52 for imparting the oscillatory movements to the second folding blade 54. By an inspection of Figure 1, it will be seen that the shaft 124 which is driven by the spur gear 123, is provided with a bevel pinion 141 which meshes with a bevel gear 142 which is keyed to the shaft 78 for driving the fourth conveyer in the manner hereinbefore described. Referring now to Figure 16, the shaft 78 carries a spur gear 143 which meshes with an idler 145, a second idler 146 meshes with the idler 147 which is in mesh with another idler 148. An 100 idler 149 transmits power to a spur gear 150 which drives the pressure roll 89. A spur gear 151 which meshes with the spur gear 150 drives the pressure roll 90. It will be 105 seen from Figure 7 that the transverse shaft 78 is provided on the end opposite to gear 142 with a spur gear 152. Gear 152 is in mesh with a spur gear 153 which is integral with a sleeve 154 which carries a cam 155. The cam 155 has running contact with a cam roller 156 which is mounted in a cam lever 157 which is keyed to the rock shaft 87 for oscillating the fourth folding blade 85. As shown in Figure 3, whenever it is desired 110 to omit the fourth fold, the folding blade 85 115 120 125 130 135 140 145 150 155 160

may be rendered inoperative by any suitable means not shown and the cam 83 and front gage 82 adjusted to release the folded sheet to fall upon the upper run of the conveyer 5 belts 88. For this purpose, a section 156' of the plate which normally constitutes a portion of the table for supporting the trailing sheet, may be moved upwardly on its pivot 157 into a position in which it projects 10 across the normal path of a sheet and constitutes a switch for deflecting the forward edge of said sheet onto the conveyer tapes 88. In Figure 23 of the drawings is shown a modified construction of a sheet 15 gripping element, said modification comprising a hollow post 158 set into suitable sockets formed in the cross bar 159 of the carriage. Threaded into the bar 159 is a set screw 160 upon the inner end of which is seated one end of a compression spring 161. The upper end of compression spring 161 exerts a pressure on the gripper element or plunger 162 which projects above the upper end of the hollow post 158. A gripper jaw 20 163 is adapted to cooperate with the yieldable jaw 162, the several jaws 163 being mounted upon a rock shaft 164 to be operated in the manner hereinbefore pointed out.

In the embodiment of my invention shown 30 in Figures 24, 25 and 26, a feed table 165 is provided with a sliding plate 168. Depending from the sliding plate 168 is a block 169 which carries a laterally projecting pin 170 which is provided with a slidable bearing 35 mounted in the slot 171 in the upper end of a lever arm 172 which is mounted upon a rock shaft 173. Keyed to the shaft 173 is an arm 174 which is connected by a rod 175 with one arm 176 of a cam lever pivoted on a stud 177, the other arm 178 of said cam 40 lever being provided with a roller 179 which runs on a cam 180 on a cam shaft 181. A spring 182 holds the cam roller to the cam 180. Keyed to the cam shaft 181 is a second cam 182' upon which runs a cam roller 183 mounted in a cam arm 184 for oscillating the arms 185 which carry the folding blade 186. Said folding blade is adapted 45 to depress the folded edge of a sheet through the gap 187 of the table 188 and into the bight of a pressure roller 188' and the feed tapes 189. In this embodiment of my invention, a power driven shaft 190 has keyed thereto laterally spaced sprockets 191 which 50 drive the conveyer chains 192 for propelling the sheet conveying carriages now to be described, the sprocket chains having driving engagement with each of said carriages. Referring to Figures 25 and 26, each carriage 55 comprises a fixed plate or bar 193 which carries a rod 194. Pivotally connected to the plate 193 by means of the rod 194 is a movable plate 195, said movable plate being 60 actuated upon by a spring 196 on the rod 194 65 for moving the plate 195 down into grip-

ping engagement with the plate 193 whenever the pressure which separates said plates is relaxed. Plates 193 and 195 are provided with notches 197 and 198 which are staggered with respect to similar notches formed 70 in the forward edge of the reciprocatory sheet feeding plate 168. The movable plate 195 is provided with suitable grippers 199 which are arranged to correspond to the notches in the forward edge of the reciprocatory feed plate. As the carriage is moved into the position shown in dotted lines in Figure 25, a gear segment 200 which is rigidly connected with the movable plate 195 is brought into engagement with a fixed segment 201 which revolves a cam arm 202 in an anti-clockwise direction until a cam roller 203 in the outer end of said arm is brought into engagement with a fixed cam 204. As the grippers move upwardly to 80 the upper run of the conveyer chains and beneath the reciprocatory plate 168 in its rearward position, said plate moves forwardly with the forward edge of the sheet in position to be gripped. At the proper 85 moment which is timed to correspond to the drop in cam 204, the cam roller 203 drops towards the shaft 190 and permits the spring 196 to effect a rapid closing of the gripper jaws. The sheet thus led off is moved forwardly on the upper run of the conveyer around the forward end thereof, and rearwardly into position against the front edge gages 205. At this stage of its progress, 90 the gripper jaws are released by the cam 100 roller 203 striking a cam 204' which may be adjusted in position by screw rods 205' provided with a crank 206. The driving connections comprise a gear 207, meshing with a gear 208 and transmitting power by 105 a train of gears 209, 210, 211 and 212 to a gear 213 which drives the feed tapes 189. An idler 214 meshes with a large spur gear 215 for driving the cam shaft 181. The 110 operation of my improved machine will be obvious from the drawings and the description hereinbefore given.

It will be observed that in the operation of the improved machine above described, the sheet material is carried into the machine 115 for the folding operation by travelling gripper devices, which engage the forward edge of the sheet material and pull or drag the same by its leading edge into the desired position. In this operation, the position 120 of the sheet material is gaged by registering devices operating upon the leading edge. This feeding operation in a folding machine is broadly new, and by reason of this difference in operation I am able to fold not 125 only the usual paper sheets but sheets of cloth or any textile fabrics including flat laundry articles such as towels, napkins, etc. The improved machine has been designed 130 primarily to perform the folding operations

upon sheet materials without the use of the ordinary folding rollers, but I will have it understood that the sheet conveying or feeding principle involved is applicable as well to the roller folding machines as to the gripper type of folding machine described and specifically claimed in this application.

In adapting the machine to any one of its many uses, there is no change in principle, but only slight rearrangements of parts to suit the form of folding desired for the particular class of work.

I claim:

1. In a machine of the character described, a traveling conveyer provided with means for gripping the front edge of a sheet, a folder blade past which a sheet is conveyed by said front edge sheet gripping means, means for operating said sheet-gripping means to release the sheet and for bringing the sheet to rest in position to be folded by said folder blade, and folded edge gripping means movable continuously in one direction past the folder blade and cooperating therewith to fold said sheet, said folded edge gripping means being suitably mounted to convey said folded sheet away from said folding blade.

2. In a machine of the character described, the combination with a fixed support for a sheet, of a folder blade arranged to fold a sheet at rest, travelling grippers movable from a position in which they close on the front edge of a sheet on said support to a position in which they release said sheet in a position of rest to be folded by said folder blade, a front edge gage for determining such position of rest, and a cam for operating said grippers to release said sheet, said front edge gage and gripper cam having a common adjustment to vary the line of folding with respect to the forward edge of the sheet.

3. In a machine of the character described, sheet gripping means, means for conveying said sheet gripping means over a predetermined path of movement, other sheet gripping means, means for conveying said other sheet gripping means over a predetermined path of movement, and a folding blade past which both of said sheet gripping means are conveyed, said folding blade cooperating with one of said sheet gripping means for folding a sheet.

4. In a machine of the character described, a sheet folding blade pivoted on a fixed axis, a plurality of grippers arranged in a series, means for moving said grippers into and out of position to cooperate with said folding blade at periodic intervals, a second folding blade pivoted on a fixed axis distant from the first, a second series of grippers, and means for moving the second series of grippers into and out of

position to cooperate with said second folding blade.

5. In a machine of the character described, the combination of a sheet folding blade arranged to fold a sheet at rest, a second folding blade arranged to fold the folded sheet at rest, and folded edge gripping means movable from a position in which it is operated to grip the folded edge of the sheet folded by the first mentioned folding blade to a position in which it is operated to release the folded sheet in a position of rest to be folded by the second mentioned folding blade.

6. In a machine of the character described, sheet folding blades arranged at a distance from each other and pivotally mounted on fixed axes, folded edge grippers cooperating with one of said folding blades for folding a sheet, means for moving said folded edge grippers from sheet-folding position toward and past the other folding blade, means for gaging the folded edge of the sheet and releasing the folded edge grippers for bringing the folded sheet to rest in position to be folded by the other folder blade, and means for operating said folding blades.

7. In a machine of the character described, the combination with sheet folding means adapted to present the folded edge of a sheet into a predetermined position, sheet gripping means, means for moving the sheet gripping means over a predetermined path of movement to bring it into position to close upon said folded edge, means for closing said sheet gripping means, and means for coordinating the movements of the sheet folding means and the means for moving said sheet gripping means for delivering the folded edge of a sheet at the instant said gripping means closes, said sheet gripping means including a rock shaft provided with a gear pinion, an oscillatory segmental gear travelling with said sheet gripping means and meshing with said gear pinion, and cams disposed along the path of said sheet gripping means for opening and closing said sheet gripping means, said segmental gear being provided with a cam arm adapted to be actuated by said cams.

8. In a machine of the character described, the combination with sheet folding means, of a conveyer for positively gripping a sheet and moving it over a normal path into position to be operated upon by said folding means, means for registering and releasing a sheet from the sheet gripping conveyer, and means for deflecting said sheet before it reaches folding position, said registering and releasing means being adjustable to a position in which it operates said sheet gripping conveyer to release said sheet before said sheet reaches position to be folded.

9. In a machine of the character de-

- scribed, the combination with sheet folding means, of a conveyer for positively gripping a sheet and moving it over a normal path into position to be operated upon by 5 said folding means, means for registering and releasing a sheet from the sheet gripping conveyer, and means for deflecting said sheet before it reaches folding position, said registering and releasing means being adjustable to a position in which it 10 operates said sheet gripping conveyer to release said sheet before said sheet reaches position to be folded, said deflecting means comprising a plate section normally in position to have a sheet conveyed thereover into sheet folding position and adapted to swing into a position across the normal path of said sheet to deflect it from said normal path.
10. In a machine of the character described, the combination with a sheet folding blade, of sheet gripping means including a rock shaft for opening and closing said sheet gripping means, said rock shaft, 15 being provided with a gear pinion, an oscillatory gear meshing with said pinion and provided with a cam arm, means for conveying said gripping means into and out of position to cooperate with said folding blade, and a cam disposed along the path of said sheet gripping means to engage said cam arm.
11. In a folding machine, the combination of sheet folding means, traveling sheet gripping means including a rock shaft provided with a gear pinion and an oscillatory gear meshing with said gear pinion and provided with a cam arm, said sheet gripping means being adapted by its movement 20 to be brought into a position to receive the folded edge of a sheet folded by said sheet folding means, and cams suitably disposed along the path of said sheet gripping means and cooperating with said cam arm for opening and closing said sheet gripping means.
12. In a machine of the character described, the combination with a folding blade, of a traveling gripper for moving a sheet into position with respect to said folding blade, a gage for determining the position of said sheet, and means for releasing said sheet from the gripper depending upon the position of said gage.
13. In a machine of the character described, the combination with a folding blade, of a travelling gripper for moving a sheet into position with respect to said folding blade, said gripper having relatively movable jaws, a cam for opening and closing the jaws of said gripper, a gage for determining the position of said sheet with respect to said folding blade, and means for simultaneously adjusting the position of said cam and gage.
14. In a machine of the character described, the combination with a folding blade, of a traveling gripper for moving a sheet into position with respect to said folding blade, a transverse bar adjustable in 70 the direction of the sheet feed, a front gage carried by said transverse bar, and means mounted on said bar for opening said gripper.
15. In a machine of the character described, means for conveying a sheet into suitable position to be folded and permitting it to come to rest in said position, means for folding said sheet and conveying it from said folding position, the last said 80 means including folded edge grippers, other folded edge grippers movable into and out of position to grip the folded edge of said sheet as it is released by the first mentioned folded edge grippers, and means for opening and closing said grippers to effect the transfer.
16. In a machine of the character described, sheet gripping means movable over a predetermined path, oscillatable sheet 90 folding means adapted to present the folded edge of a sheet into the path of said sheet gripping means, means for moving the sheet gripping means into position to close upon said folded edge, means for closing said 95 sheet gripping means, and means for co-ordinating the movements of the sheet folding means and the means for moving said sheet gripping means for delivering the folded edge of a sheet at the instant said 100 gripping means closes.
17. In a machine of the character described, a folding blade, a front sheet gage for determining the position of a sheet with respect to said folding blade, a gripper for 105 said sheet, and means for conveying said gripper past said front gage, said gripper comprising relatively movable jaws and a yieldably mounted sheet gripping element in one of said jaws, said front gage being provided with means for releasing said gripper.
18. In a machine of the character described, the combination with sheet-folding means, of sheet-gripping means engaging the forward edge of a sheet and movable 115 over a normal path for conveying said sheet into position to be folded by said sheet-folding means, means including a pivoted plate for supporting said sheet as it trails behind said gripping means, said plate being 120 movable about its pivotal axis into a position to deflect said sheet from its normal path, and means for operating said gripping means to release the sheet, said operating means being adjustable in position to 125 release the sheet in position to be folded or to be deflected without being folded.
19. In a machine of the character described, the combination of a sheet folding blade arranged to fold a sheet at rest, a second fold- 130

- ing blade arranged to fold the folded sheet at rest, and folded edge gripping means movable from a position in which it is operated to grip the folded edge of the sheet 5 folded by the first mentioned folding blade to a position in which it is operated to release the folded sheet in a position of rest to be folded by the second mentioned folding blade, the first mentioned folding blade 10 and said folded edge gripping means having coincident paths of travel at the moment the folded edge of a sheet is presented to said gripping means by the first mentioned folding blade.
- 15 20. In a machine of the character described, a sheet support, front-edge sheet gripping means movable thru one run of a closed path in a direction away from said sheet support, and afterwards thru a return 20 run of said closed path, means for closing said gripping means on the forward edge of a sheet on said sheet support, means for opening said gripping means during said return movement for releasing said sheet, 25 and means for folding said sheet as it is displaced from a position of rest in which it is left by said gripping means.
21. In a machine of the character described, a sheet support, front-edge sheet gripping means movable thru one run of a closed path in a direction away from said sheet support, and afterwards thru a return run of said closed path, means for closing 30 said gripping means on the forward edge of a sheet on said sheet support, means for opening said gripping means during said return movement for releasing said sheet, and means for folding said sheet as it is displaced from a position of rest in which it is left by said gripping means, said folding 35 means including a folding blade which traverses the path of said sheet during the return run of said gripping means.
22. In a machine of the character described, a sheet support, front-edge sheet gripping means movable thru one run of a closed path in a direction away from said sheet support, and afterwards thru a return run of said closed path, means for closing 40 said gripping means on the forward edge of a sheet on said sheet support, means for opening said gripping means during said return movement for releasing said sheet, a folding blade which operates upon said sheet in the position of rest in which it is left by said gripping means, and a folded edge gripper movable into and out of position to cooperate with said folding blade for folding said sheet.
- 45 23. In a machine of the character described, a sheet-folding blade, a front edge gripper for moving a sheet into sheet-fold- 50 ing position with respect to said blade, means for operating said gripper to release a sheet in position to be folded or in an other position before the sheet reaches folding position, a second front edge gripper traveling in a path which partly coincides with the path of the first mentioned gripper, said second gripper being adjustable to 55 cooperate with said folding blade in one position for folding the sheet and with the first front edge gripper in the other position for transferring the sheet, and means for operating the second front edge gripper to 60 close on said sheet in either of said positions to which the second gripper is adjustable.
- 65 24. In a machine of the character described, a sheet-folding blade, a front edge gripper for moving a sheet into sheet-fold- 70 ing position with respect to said blade, means for operating said gripper to release a sheet in position to be folded or in an other position before the sheet reaches folding position, a second front edge gripper traveling in a path which partly coincides with the path of the first mentioned gripper, said second gripper being adjustable to 75 cooperate with said folding blade in one position for folding the sheet and with the first front edge gripper in the other position for transferring the sheet, and means for operating the second front edge gripper to 80 close on said sheet in either of said positions to which the second gripper is adjustable.
- 85 25. In a machine of the character described, the combination with a sheet-folding blade, of sheet conveying means including grippers arranged in transverse series to grip the folded edge of a sheet as it is 90 folded and presented by said folding blade, other sheet conveying means including grippers arranged in transverse series to grip the folded edge of said sheet, the transverse series of grippers of both conveying means 95 having portions of their paths coincident, and means for simultaneously opening one series of grippers and closing the other series of grippers to transfer the folded sheet from one conveyer to the other, while said grippers are passing thru said coincident portions of their paths.
- 100 26. In a machine of the character described, the combination with a sheet-folding blade, of sheet conveying means including grippers arranged in transverse series to grip the forward edge of a sheet, each of said grippers having relatively movable jaws and one of said jaws being provided 105 with yieldable elements whereby the gripper is adapted to yieldably engage a sheet under a diminishing pressure for a briefly extended interval after the opening movement of said grippers has begun, means for opening said grippers at a predetermined 110
- 115
- 120
- 125
- 130

point in their travel, and sheet-gaging means for stripping said sheet from the grippers under such diminishing pressure.

27. The combination with a sheet support, of sheet-gripping means travelling in a closed path including a run extending away from the forward extremity of said sheet support, said sheet-gripping means being adapted to grip the forward edge of a sheet on said sheet support, sheet-folding means past which said sheet-gripping means drags said sheet into position to be folded by said sheet-folding means, means for gaging the forward edge of said sheet for registering it with respect to said folding means, and means for operating said sheet-gripping means to release the forward edge of said sheet when it reaches sheet-folding position.

28. In a machine of the character described, the combination of a sheet folding blade arranged to fold a sheet at rest, folded edge gripping means movable into and out of a position to grip the folded edge imparted by said folding blade, other folded edge gripping means movable over a path including a portion which is tangential to the path of the first mentioned folded edge gripping means, and means for cooperatively operating the first and second mentioned folded edge grippers whereby the folded edge is released by the first mentioned folded edge gripping means and gripped by the second mentioned folded edge gripping means.

29. In a machine of the character described, the combination of a sheet folding blade arranged to fold a sheet at rest, folded edge gripping means movable into and out of a position to grip the folded edge imparted

by said folding blade, other folded edge gripping means movable over a path having a portion thereof coincident with a portion of the path traveled by the first mentioned folded edge gripping means, means for cooperatively operating both folded edge gripping means whereby the folded edge is released by the first mentioned folded edge gripping means and gripped by the second mentioned folded edge gripping means, a folding blade past which the second mentioned folded edge gripping means extends, and means for operating the second mentioned folded edge gripping means to release the folded sheet in a position of rest to be folded by the last mentioned folding blade.

30. In a machine of the character described, the combination of a sheet folding blade arranged to fold a sheet at rest, a second folding blade arranged to fold the folded sheet at rest, folded edge gripping means for receiving the folded edge of a sheet from the first mentioned folding blade and releasing said folded sheet in a position of rest to be folded by the second mentioned folding blade, other folded edge gripping means movable over a path partly coincident with the path of the first mentioned folded edge gripping means and partly coincident with the path of said second mentioned folding blade, and means for operating the first mentioned folded edge grippers either in a position to deliver the once folded sheet directly to the second mentioned folded edge grippers or in a position to release the once folded sheet to come to rest in position to be folded again by the second mentioned folding blade.

EARL D. RADER.
